United States Patent Office.

DEXTER B WINGATE, OF NATICK, ASSIGNOR TO NEEDHAM C. MILLETT, OF SALEM, MASSACHUSETTS.

Letters Patent No. 79,713, dated July 7, 1868.

IMPROVEMENT IN APPARATUS FOR PRINTING UPON GLASS.

The Schedule referred to in these Letters Patent and making part of the same.

TO ALL WHOM IT MAY CONCERN:

Be it known that I, DEXTER B. WINGATE, of Natick, in the county of Middlesex, and State of Massachusetts, have invented a new and useful Improvement in Printing Uneven Surfaces; and I do hereby declare that the following is a full, clear, and exact description of the same, in connection with the drawings forming a part of this specification.

The nature of my invention is to print upon unyielding irregular surfaces, and consists in an arrangement by which a movable type-block, made of firm elastic material, similar to vulcanized rubber in its mechanical properties, is combined with suitable mechanical devices.

To enable others skilled in the art to make and use my invention, I will proceed to describe its construction and operation.

In the drawings—

Figure 1 represents a top view.

Figure 2 represents a vertical section through the line *a b* of fig. 1.

The type-block D is made from a composition of glue and molasses, similar to that used for printers' inking-rollers. Ordinary metallic type being set up to form the text required, a plaster cast is taken from this, and into this, as a mould, the composition is poured, being first melted for that purpose. This forms the elastic type-block, and is properly mounted on the movable support C, which is raised by the lever L; for the purpose of inking the type without soiling the ways H H. The ways H H are adjusted on a line even with the top of the type, and are held in any set position by the tightening-screws K K.

In printing labels on bottles, the gauge E being adjusted at the proper distance from the type-block D, which gives the required distance of the label from the bottom of the bottle, the lever L is first raised, and the ink applied to the type-block with a common inking-roller. It is then lowered on to the surface of the frame X, which supports it firmly, and, the ways H being adjusted to the level of the type-block D, the bottom of the bottle is placed against the adjustable gauge E, and rolled over the surface of the type-block D, which yields to the inequalities of the glass, giving a clear and exact impression of the type.

In printing labels, designs of any required style may be cast in the same way, and, by the use of varnish or sizing, and bronze-powders of various colors, a very elegant and desirable label is produced, quickly, and at a cheap rate, and the label is not liable to be separated from the bottle, as in the ordinary way of attaching it.

Having thus stated the nature of my invention, what I claim therein as new, and desire to secure by Letters Patent, is—

Forming a type-block of an elastic yielding material, and its use in combination with the adjustable ways H, adjustable gauge E, and lever L, operating in connection with the movable support C, for the purpose substantially as described and set forth.
